UNITED STATES PATENT OFFICE

2,615,517

DISPENSER FOR CUTTING AND
SUPPORTING TAPETripoli J. Di Cicco, Concord, Mass., assignor to
Electro Products Company, a partnership

Application June 21, 1948, Serial No. 34,311

1 Claim. (Cl. 164—61)

1

This invention relates to improvements in apparatus for cutting and dispensing tape, particularly pressure-sensitive adhesive tape.

It is an object of the invention to provide a device to receive a roll of tape and which is adapted to dispense the same in one or more strips of predetermined length suitable for application to a package or other article at hand to seal or secure the same. In a particular embodiment of the invention, a multi-bladed knife is provided to sever and support a plurality of such strips in position for convenient use.

Another object of the invention is to provide a device which may be readily adjusted to dispense strips in various selected lengths most suitable for the particular purpose of the user.

A further object is the provision of relatively compact and simple apparatus operable in its entirety by a single operating means.

Other and further objects and advantages will be apparent from the following detailed explanation taken in conjunction with the accompanying drawings wherein a preferred embodiment of the principles of the invention has been selected for exemplification.

In the drawings:

Fig. 1 is a perspective view of a tape dispensing device as comprehended by the present invention;

Fig. 2 is a top plan view of the device of Fig. 1 having the cover removed to show the supported roll of tape and the working parts of the dispensing mechanism;

Fig. 3 is a vertical sectional view taken on the line 3—3 of Fig. 2 looking in the direction of the arrows;

Fig. 4 is a fragmentary vertical sectional view taken on the line 4—4 of Fig. 2 looking in the direction of the arrows;

Fig. 5 is a fragmentary vertical sectional view taken on the line 5—5 of Fig. 2 looking in the direction of the arrows;

Fig. 6 is a vertical sectional view taken on the line 6—6 of Fig. 2 looking in the direction of the arrows;

Fig. 7 is a vertical sectional view taken on the line 7—7 of Fig. 3 looking in the direction of the arrows;

Fig. 8 is a rear elevational view of the rotatable multi-bladed cutting and strip supporting knife;

Fig. 9 is a detail perspective view of the knife actuating crank arm and associated parts as hereinafter described; and

Fig. 10 is a perspective view looking toward the rear face of the knife.

Referring more particularly to the drawings

2

wherein like numerals refer to like parts, 10 designates a suitable casing or housing having a cover 12 removably secured by spring fingers 14 and 16, respectively, which engage the adjacent inner sidewall portions of the casing 10. Cover 12 conveniently is provided with a hollow hand grip portion 13. A pair of opposed vertical slots 18 are cast or otherwise provided in the inner side walls toward the rear of casing 10 to receive a fixed shaft 20 having a rotatable cylindrical support 22 upon which is frictionally mounted a roll of tape T, as shown. Certain kinds of adhesive tape have a tendency to telescope on the roll and, in order that the tape may be held in constant alignment with the dispensing mouth, the support 22 is freely slidable axially of the shaft 20 to provide a floating support for the tape roll T.

For maintaining the tape in proper alignment with the dispensing mechanism, a guide assembly 20 is interposed and is supported upon opposed shoulders 24 integrally cast or otherwise provided on the sidewalls of casing 10 and each having an upright pin member 26. The guide assembly 25 is composed of a cross-strap 28 carrying an end flared snap spring 30, each apertured to receive the pins 26. The apertures 32 at opposite ends of the cross-strap 28 are elongated and enlarged at one end initially to receive the pins 26 which act to displace slightly the overhanging portion of spring 30 when positioning the guide assembly. The cross-strap 28 is then drawn slightly forwardly, the pins 26 riding in the elongated slots 32 until registering with the apertures 34 of the spring 30 which then snaps downwardly over the pins to secure the assembly in position.

Secured to cross-strap 28 and depending vertically is a pair of spaced legs 36 carrying a friction roller 38 at their lower ends in position to engage the tape strip and exert pressure thereon requisite for proper feeding of the tape. Pivotaly attached to the legs 36 and extending rearwardly thereof is a pair of arms 39 for supporting the channelled guide roller 40 which is urged into constant engagement with the periphery of the tape roll T by tension spring 42. It will be apparent that the channelled guide roller 40 holds the peripheral portion of the roll T from which the tape is unreeled in fixed alignment with the dispensing mechanism at the front of the casing and any adjustments necessitated by warping or telescoping of the roll are effected by sliding movement of the roll support 22 axially of the shaft 20.

The tape feeding and dispensing mechanism is supported in general by an upright bracket member 44 fixed in the forward part of casing by screws 46 countersunk in the casing bottom wall. A shaft 48 extends transversely of the bracket 44 and through an aperture in the side-wall of the casing 10 to receive an operating handle or lever 50. Keyed to a sleeve 49 carried intermediate the ends of the shaft 48 are spaced feeding wheels 52 having knurled peripheries over which the tape is trained after passing the pressure roller 38. For removing the tape from the feeding wheels 52, two pairs of idler wheels 54 having notched peripheries are rotatably supported between the relatively larger wheels 52 and extend tangentially of the wheels 52 so as to support the advancing tape in a horizontal position. Also supporting the tape strip forwardly of the idler wheels 54 and assisting in advancing the tape is a small feed wheel 56 which receives its drive from a pinion 58 supported by the bracket 44 and linked to the feed wheels 52 so that the wheels tend to rotate simultaneously.

Drive for the wheels 52 is derived from ratchet wheel 60 fixed to the sleeve 49 adjacent one of the wheels 52 and ratchet pin 62 carried by a U-shaped bracket 64 which depends from shaft 48 and tends to rotate therewith. The lower arm of bracket 64 which supports ratchet pin 62 rides in an arcuate slot 66 provided in the wall of upright bracket 44. The handle 50 which turns shaft 48 and ratchet pin bracket 64 bears against the tension of spiral spring 68 during its forward feeding and cutting stroke upon the completion of which the handle 50 and members carried thereby are abruptly returned by the spring 68 to normal position. The operation is such that forward stroke of the handle 50 will tend to rotate the shaft 48 and bracket 64 and, by means of ratchet connections 60 and 62, in turn tend to rotate simultaneously the wheels 52 and 56, thus advancing a length of the tape outwardly beyond the cutting mechanism at the forward dispensing portion of the apparatus.

Cutting knife 70 is adapted to be rotated one-quarter of a revolution upon the rearward or return stroke of handle 50. To this end, an arm 72 is pivotally attached to a stub shaft 74 secured to the bracket member 44 and carries at its free end an upright link 76. The upper end of link 76 is pivoted to a crank arm 78 that is mounted to swing upon a knife shaft 80. Shaft 80 is supported by threaded engagement in the upper end of an extension 44a of bracket 44. The knife shaft projects through a shield 86 which blocks the cut out front end wall of casing 10. A flat spring element 82 is of inverted U shape and one of its legs is traversed by the knife shaft 80 so that this spring element, as a whole, swings bodily with crank arm 78. The other or free leg of the spring element is pierced to receive the end of a ratchet pin 84 that is mounted for sliding movement through the crank arm. The engagement of the rear end of pin 84 with the free leg of the spring element forces said element to partake of the swinging movement of the crank arm. This spring element thrusts pin 84 outwardly through the shield and into engagement with the rear face of the hub portion of the knife 70 (see Fig. 10) where it acts as a pawl by engaging in the ratchet like recesses 90. An arcuate slot 86a is formed in shield 86 to permit the swinging movement of the pin along with the crank arm. In its movement from one ratchet recess 90 to another the end

of the pin 84 rides over the flat rear face 88 of the hub of knife 70 which face is held against shield 86 by spring means hereinafter described. Thus the pin constitutes, in effect a pawl and the notches constitute in effect ratchet surfaces in which said pawl or pin engages.

For initiating operation of the tape cutting mechanism above described, the inner end of handle shaft 48 carries a cam 94 to bear against arm 72 which tends to be urged upwardly by spring 96, as best shown in Fig. 5. Normally arm 72 is depressed by the cam 94 but when handle 50 approaches the end of its forward thrust the reduced surface of cam 94 is swung by the shaft 48 to its lowermost position permitting the arm 72 to elevate the link 76 which in turn tends to swing crank arm 78 and pin 84 carried thereby upwardly and toward the left in Fig. 6. During this movement, the cam end of pin 84 which projects through the arcuate slot in shield 86 rides upwardly along the elevated surface 88 of knife 70 until it reaches the uppermost notch 90, into which the pin is seated by the action of its supporting spring 82. Thus the pin 84 constitutes, in effect, a pawl and the notches constitute in effect, ratchet surfaces in which said pin or pawl engages. When handle 50 is released and is returned abruptly to normal position by its spring 68, the enlarged face of cam 94 will simultaneously depress arm 72 and, through connecting link 76 and crank arm 78 carrying pin 84 which now is seated in one of the notches 90, move the knife 70 one-quarter of a revolution, sufficient to sever the length of tape projecting beyond the shield 86.

The rotatable blades of knife 70 coact with a fixed blade plate 98 carried by bracket 44 and which projects through shield 86 immediately above the path along which the tape is advanced by the drive wheels 52 and 56. The blade 98 may be removed or adjusted as required by bolts 100 which secure the same to the bracket 44. Knife 70 is ordinarily self adjusting by a retaining coil spring 102 contained within a cone-shaped cup 104 secured to the shaft 80 at its front or outer end. The cutting blades of knife 70 are relatively wide so as to provide a supporting ledge for each severed length of tape, as best shown in Fig. 1. Thus, upon four actuations of the handle 50, four lengths of tape may be severed from the roll and each supported upon one of the blades in convenient position for the operator to grasp and apply to the package or other article at hand. As is illustrated in Fig. 1, the severed lengths of adhesive tape adhere to those portions of the edges of the blades with which they contact. As the blades of the knife move upwardly past the fixed blade 98 to coact therewith the upper face of each of the movable blades comes into contact with the adhesive face of the tape with such pressure, in the act of cutting, that the adhesive tape sticks to the blade edges. These edges are thick enough to provide distinct ledges to which the severed portions of the tape may cling and be carried around to advanced positions. The engagement of the severed strips with these ledges and the thickness of said ledges, is such that the strips stand out in the direction of the axis about which the knife revolves and parallel with said axis as shown in Fig. 1. Only the end portions of the strips are so engaged with the blades, leaving their major portions outstanding, to be readily grasped by the user. Thus a clerk desiring to seal a package 75 may, by operating handle 50 four times, have

four severed pieces of tape presented for ready application to such package.

To prevent the blades of knife 70 from turning or tending to rotate further when the severed lengths of tape are pulled off, a pin 106 projects through an aperture in the shield 86 to engage the blade adjacent and to serve as a stop when the knife 70 has completed a turn and is at rest. Pin 106 is supported by a leaf spring 108 secured to the rear face of shield 86 and tending normally to urge the pin inwardly out of the path of the rotatable blades. The spring 108 however is engaged by crank arm 78 in a cam action which synchronizes movement of the pin 106 with the blades so that the pin is projected into operative position without interference with cutting action of the blades.

The lengths of tape which may be severed, for most purposes from $1\frac{1}{8}$ inches to $2\frac{1}{2}$ inches, may be predetermined by simple adjustment of the throw of handle 50 which controls the extent of movement of the tape advancing wheels. To this end, handle shaft 48 is provided with a transversely extending fixed pin 110 which abuts against a stop 112 carried by bracket 44 to limit the forward thrust of handle 50. In its opposed extremity of movement pin 110 abuts against a plug 114 which, as best shown in Fig. 5, is threaded to an adjusting screw 116 having a knurled head 118 disposed for ready access at the front or dispensing end of the apparatus. By rotating the knob 118 the position of plug stop 114 may be adjusted to vary the extent of the rearward limit of the throw of handle 50.

It will be understood that the particular elements and arrangement and construction of the various parts herein shown and described are exemplary only of a preferred form of the present invention which embraces such modifications as come within the scope of the following claim.

What I claim is:

In a machine for dispensing tape of the kind having one plain face and one adhesive face the combination with a casing having a dispensing

mouth, a fixed blade plate spanning said mouth, a movable cutting mechanism comprising a plurality of substantially radially extending blades, means for imparting step by step rotary movement to said cutting mechanism to move said blades across the fixed blade plate in cutting co-action therewith, means controlled by said first named means for feeding the tape through said mouth while said cutting mechanism is stationary across and beneath the blade plate with its plain side toward the blade plate and its adhesive side toward the edge of the advancing blade of the movable cutting mechanism, said blades having outwardly projecting ledges adjacent the cutting edges of the blades to which ledges the adhesive sides of the cut off portions of the tape adhere, the forward feeding of the tape being to a degree to cause the cut off portions of the tape to project materially beyond said blades and the said ledges being of such width in proportion to the lengths of tape cut off as to hold and carry successively cut off portions to a plurality of advanced positions with said cut off portions outstanding from the blades in substantial parallelism with each other.
